UNITED STATES PATENT OFFICE

A. JUDSON PALMER, OF KEANSBURG, NEW JERSEY

DESIGN FOR A RECORDING DEVICE

Application filed February 11, 1932. Serial No. 42,892. Term of patent 14 years.

To all whom it may concern:

Be it known that I, A. JUDSON PALMER, a citizen of the United States, residing at Keansburg, in the county of Monmouth and State of New Jersey, have invented a new, original, and ornamental Design for a Recording Device, of which the following is a specification, reference being had to the accompanying drawing, forming part thereof.

The figure is a perspective view of the recording device, showing my new design.

I claim:

The ornamental design for a recording device, as shown.

A. JUDSON PALMER.
